UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A EWER.

SPECIFICATION forming part of Design No. 27,651, dated September 21, 1897.

Application filed August 7, 1897. Serial No. 647,501. Term of patent 3½ years.

To all whom it may concern:

Be it known that I, WILLIAM H. GRINDLEY, a citizen of Great Britain, residing at Congleton, in the county of Cheshire, England, have 5 invented a certain new and original Design for a Ewer; and I do hereby declare the following to be a full, clear, and exact description of the same, reference being had to the accompanying drawings, forming a part hereof.

In the drawings, Figure 1 is a side view of a ewer embodying my design, and Fig. 2 is a section of the same on the plane of the line 2 2 in Fig 1.

The leading features of my design are as follows: The body of the ewer A is composed of 5 a number of panels $a' a'' a'''$, &c., bounded by lines $b' b'' b'''$, &c., which form the edges of the panels and which are continuous curves. The panels are about the same width around 20 the ewer, which is symmetrical in cross-section. Toward the top of the body it curves sharply inward at $c' c'' c'''$, &c., and narrows to form the neck N, which curves outward at L to form the lip and at II, to which the 25 handle is attached. Between the neck and body of the pitcher is a band B, nearly horizontal in position and divided into sections or panels $p' p'' p'''$, &c., by means of the prolongations of the lines $b' b'' b'''$, &c.

The base D of the ewer terminates in points 30 $d' d''$, &c., irregularly disposed, which touch the surface upon which the ewer rests in the horizontal plane. The base is provided with upwardly-projecting slightly-embossed ornamentation resembling oak-leaves.

Each panel of the ewer is provided at its base with an ornamentation O of conventionalized oak-leaves in relief, and each alternate panel has such ornamentation O' smaller than the one next to it. At its top each panel 40 is provided with downwardly-projecting embossed ornamentations Q of about the same size and resembling a fluer-de-lis somewhat in style, though composed of forms like oak-leaves.

45 The handle E is a reverse curve provided with outwardly-projecting knobs.

What I claim is—

The design for a ewer substantially as shown and described.

In testimony whereof I have signed this specification in the presence of two subscribing witnesses.

WILLIAM H. GRINDLEY.

Witnesses:

W. C. WARNER,
JOHN H. COPESTAKE.
